A. J. FISHER.
WASHING MACHINE HEATER
APPLICATION FILED JUNE 16, 1919.

1,388,941.

Patented Aug. 30, 1921.

UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

WASHING-MACHINE HEATER.

1,388,941.

Specification of Letters Patent. Patented Aug. 30, 1921.

Application filed June 16, 1919. Serial No. 304,573.

To all whom it may concern:

Be it known that I, ALVA J. FISHER, a citizen of the United States, residing at Evanston, in the county of Cook and State 5 of Illinois, have invented certain new and useful Improvements in Washing-Machine Heaters, of which the following is a specification.

My invention relates to a washing machine heater.

It is oftentimes desirable to have a clothes washing machine self-heated, as by means of a gas heater, and my invention provides a desirable, simple and commercially satisfactory washing machine and heater combination in which the heater is an attachment applicable to, and removable from, the washing machine structure without change in the latter.

Among the objects of my invention are to provide a simple, efficient heater, of the gas-burning type, advantageous means for effecting connection between the heater and the washing machine, and satisfactory provision 20 for sealing the washing machine casing and burner shell for protection of the washing machine and its operator. Other further objects of my invention will become apparent from the following description and 25 the appended claims, taken in connection with the accompanying drawings wherein Figure 1 is a side elevation with parts broken away showing a washing machine equipped with a burner in accordance with 30 my invention; Fig. 2 is a bottom plan of the heater feature, and Fig. 3 is a vertical cross section or fragment of the assemblage.

The washing machine has a casing 10, with a parti-cylindrical bottom, preferably 40 a true arc in cross section. With the agitating mechanism of the washing machine the present invention is not concerned.

The casing is carried on a frame 11, comprising end members which may, of course, 45 be of widely variant form, these end members having suitable longitudinal connection which include, for purpose of support to the heater-shell as well as strengthening the frame construction, tie-rods 12, preferably 50 located substantially as shown in Fig. 3, that is to say paralleling the casing bottom along the front and rear thereof, and close to or slightly above the bottom plane of the casing.

55 The burner shell 13 is a trough member

having widely flaring sides 14 with suitable openings 15, 16, closed ends 17, and, preferably long bottom openings 18 suitably bridged as at 19 for strength. The gas burner tube 20 extends longitudinally 60 through the shell, and is supported in the receptive openings in the end wall, this tube of course being capped as at 21 and thereby closed at one end and extending beyond the flame and equipped with a regulating valve 22 and coupling connection 23 at its other end. Hangers 24 connect the burner shell with the frame. Four of these hangers will amply support the shell, these being arranged in pairs at the respective 65 ends of the shell and extending from engagement with the latter near the bottom into engagement with the tie-rods 12. Each hanger is an extensible strap composed of 70 two sections having down-bent confronting portions connected by a bolt 25 for length and tension adjustment, each section having at its free end a hook as respectively shown at 26 and 27 for engagement with the shell at the edge of the opening 18 and with the 75 tie rods, respectively. These tension hangers therefore extend in inclined position as shown in Fig. 3, at a relatively acute angle to the flaring side walls of the shell, and from engagement with the very rigid parts 80 of the shell to engagement with the strong but somewhat resilient tie rods of the frame, and under proper tension they position the shell very firmly in contact with the bottom 85 of the casing. This form of suspension is 90 very desirable in that with one element of the suspension structure slightly resilient, adequate compensation for expansion and contraction under the heating and cooling action necessary to be met in the use of such 95 a heater is afforded.

I have found that satisfactory and close connection between the edge walls of the shell and the curved bottom of the casing may be made by mere pressure contact and 100 therefore I make the ends of the shell casing with mere seating flanges curved correspondingly with the casing; but the longitudinal edges of the side walls cannot well be maintained in mere contact with the long 105 stretch of shell without liability to such leakage of the products of combustion as will damage the finish of the casing and be most annoying and dangerous to the operator. Therefore I make provision for seal- 110

ing the edges of the shell to the casing with a suitable heat-resisting material such as asbestos-cement or putty. To this end I provide along the edge of the shell a lip 5 28, shaped to have its free edge out of contact with the casing and only its elbow or inner bend in substantial contact with the latter, this lip being concaved between the elbow and its free end to form a shallow 10 channel in which the cement will be retained. The cement body 29 will be plastered in after the shell has been connected by means of the hangers to the frame.

While I have herein described in considerable detail a specific embodiment of my invention, some of the details of which I may particularly claim for their advantages as refinements, it will be understood that many changes in the particulars of construction 20 and arrangement may be made without departure from the spirit of my invention within the scope of the appended claims.

What I claim is:

1. The combination of a washing machine frame having a casing and a supporting frame including end-members and parts inwardly projecting therefrom above the bottom level of the casing; a burner-shell having an orifice to conform to the bottom of 25 the casing, and variable-tension hangers extending upwardly from engagement with the shell into engagement with said projecting parts of the frame to press the shell-orifice snugly against the casing-bottom.

2. The combination of a washing machine frame having a casing and a supporting frame including end-members and parts inwardly projecting therefrom above the bottom-level of the casing; a burner-shell having an orifice to conform to the bottom of 40 the casing, and variable-tension hangers extending upwardly and diverging laterally from engagement with the shell into engagement with said projecting parts of the frame 45 to press the shell-orifice snugly against the casing-bottom.

3. The combination of a washing machine having a parti-cylindrical casing and a supporting frame therefor including longitudinally 50 extending tie rods, a burner shell having flaring side walls and ends conforming to the bottom shaping of the casing, and hangers detachably connecting said shell with said tie rods.

4. The combination of a washing machine having a parti-cylindrical casing and a supporting frame therefor including longitudinally 55 extending tie rods, a burner shell hav-

ing flaring side walls and ends conforming to the bottom shaping of the casing, and 60 hangers detachably connecting said shell with said tie rods, said hangers including tension-varying means.

5. The combination of a washing machine having a parti-cylindrical casing, end 65 frames, and front and back tie rods paralleling the shell near the bottom thereof to connect the end frames, a gas burner shell having end walls and flaring side walls to substantially fit the casing conformation, said 70 shell having bottom openings, and hangers having end hooks, engaging the edges of said bottom openings and said tie rods to support said shell.

6. The combination of a washing machine 75 having a parti-cylindrical casing, end frames, and front and back tie rods paralleling the casing near the bottom thereof to connect the end frames, a gas burner shell having end walls and flaring side walls to 80 substantially fit the casing conformation, said shell having bottom openings, and hangers having end hooks, engaging the edges of said bottom openings and said tie rods to support said shell, said hangers comprising 85 two parts adjustably connected by a tension-varying device.

7. The combination of a washing machine casing having a cylinder formed bottom, a gas burner shell having end and side walls 90 substantially to conform to said casing bottom, said side walls having extension lips non-conforming with the casing contour to receive sealing material.

8. The combination of a washing machine 95 casing having a cylinder formed bottom, a gas burner shell having end and side walls substantially to conform to said casing bottom, said side walls having extension lips non-conforming with the casing contour to 100 receive sealing material, said lips being concaved in cross-section.

9. A heater attachment set for washing machines comprising a trough-shaped shell containing a gas burner and having surfaces 105 for engagement with hangers, and a set of hangers each shaped at one end for engagement with such a surface of the shell and at its opposite end for engagement with a portion of the washing machine frame. 110

10. As an article of manufacture, a burner shell for attachment to a washing machine consisting of a trough-shaped structure having along its edges outwardly extending lips each concaved in cross-section.

ALVA J. FISHER.
